(57) CLAIM

The ornamental design for a footwear upper, as shown and described.

DESCRIPTION

FIG. 1 is a front perspective view of a footwear upper showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The dot-dash broken lines depict the bounds of the claim and form no part thereof. The even short dashed broken lines on the footwear upper depict stitching, which forms no part of the claimed design. The even dashed broken lines depicting a shoe sole represent environmental structure, which forms no part of the claimed design.
